Patented Oct. 9, 1917.

Fig. 3

UNITED STATES PATENT OFFICE.

FREDERICK G. KEYES, OF HOBOKEN, NEW JERSEY, ASSIGNOR TO NATIONAL AUTOMATIC REFRIGERATOR COMPANY, A CORPORATION OF NEW JERSEY.

REFRIGERATING APPARATUS.

1,242,559.

Specification of Letters Patent.

Patented Oct. 9, 1917.

Application filed August 19, 1916. Serial No. 115,745.

To all whom it may concern:

Be it known that I, FREDERICK G. KEYES, a citizen of the United States, residing at Hoboken, in the county of Hudson and State 5 of New Jersey, have invented certain new and useful Improvements in Refrigerating Apparatus, of which the following is a full, clear, and exact description.

In a former application for patent filed 10 by me on March 27, 1916, Serial No. 100,379, I have shown and described a method of and apparatus for automatic refrigeration, on which the subject of this application is an improvement. In order to convey to those 15 familiar with the art to which these inventions pertain, a clear understanding of the nature of my improvements, I may first describe generally and without special reference to its novel features, the original system 20 and apparatus and then indicate the more prominent features of the special parts for which I now seek protection by patent.

The main plan is a purely automatic system of refrigeration primarily designed for 25 household and analogous uses and comprises a distilling chamber or vessel containing a refrigerating composition made up of a solid absorbent, a solvent and a refrigerant, that is to say, ammonium nitrate water and ammonia, from which the volatile constituents 30 are driven over by the heat produced by an electric coil, into a condensing coil or chamber, whence the liquefied ammonia is directed into a refrigerating chamber until 35 the latter is full or filled to a predetermined extent. At this point the current is shut off from the heating coil of the distilling chamber, and the water directed from the coils of the condenser and caused to circulate in 40 coils in or around the distilling chamber to promote the reabsorption of the ammonia by the ammonium nitrate and water therein.

All of these functions are performed and controlled automatically by the use of suitable devices for the purpose and the proper 45 valves are used for directing the flow of water to the distilling or condensing chamber as the case may be, and check valves for permitting the ammonia to flow through one 50 passage from the distilling to the condensing chamber and through another on its return.

In the development of this system I have 55 found room for substantial improvement. While, for example, I originally condensed

the ammonia in a coil from which it proceeded directly to the refrigerating chamber, or in a special chamber from which, at given intervals, it was delivered to the refrigerating chamber in bulk, I now deliver 60 it from the condensing to the refrigerating chamber through a suitable expansion orifice, thus producing and taking advantage of the drop in temperature which is a consequence of the Joule-Thompson effect, and 65 thereby delivering to the refrigerating chamber a refrigerating liquid at lower temperature than would be permitted were the device not included in the system.

This and other features of the improved 70 apparatus are illustrated in the annexed drawings and will be described in detail by reference thereto.

Figure 1 is a diagrammatic illustration of 75 the complete system.

Fig. 2, is an enlarged sectional and partly diagrammatic view of a controlling valve used in the apparatus and Fig. 3 is an enlarged end view of the device for delivering the ammonia to the refrigerating chamber 80 in fine streams.

In the main diagram the numeral 1 designates such a device as a household refrigerator, in which there is located a refrigerating chamber 2, and the object of this system is 85 to supply this chamber with a refrigerant continuously and automatically. This result is accomplished by the following instrumentalities.

At the left of the diagram is shown a distilling chamber 3, which may be of any well known construction, and this is surrounded by an electric heating coil 4 adapted to receive energy at the proper intervals from any suitable source, such as the mains of a 95 public system of distribution indicated by the numerals 5 and 6.

In the practical use of this system or apparatus a composition of ammonium nitrate, water and ammonia is placed in the 100 distilling chamber and by the heating action of the energized coil 4 the volatile constituents of the mixture are driven over through a pipe 7, containing a check valve 8, into a condensing chamber 9.

This condensing chamber is provided with the usual water cooling coils 10, through which, when ammonia is passing into the chamber, a flow of water is maintained from a source represented by the 110

pipe 11, through a controlling valve 12 and a pipe 13, to an outlet pipe 14.

The condensing chamber 9 is connected with the refrigerating chamber 2, through a pipe 15, carrying at its end any device 16, which will deliver the liquefied ammonia to the chamber 2 through a Joule-Thompson expansion nozzle. For this purpose I secure to the end of the pipe 15, a disk 16, with two or more radial passages 17, leading from a central chamber out through the periphery and through these small passages the ammonia flows into the chamber 2, producing what is known as the Joule-Thompson effect, that is to say a substantial drop in temperature due to the passage of the fluid from a higher to a lower pressure, since the cooling water will invariably be at a higher temperature than the interior of the refrigerator.

Assuming then that the distillation of ammonia is going on, the chamber 9 gradually fills with the condensed ammonia which is slowly delivered through the disk 16, into the refrigerating chamber 2, and it will be observed that the refrigerant when it enters is deprived of its latent heat of condensation so that its action is purely that of effective refrigeration. The transfer of ammonia from the distilling to the condensing chamber continues until by the loss of ammonia the temperature of the chamber 3, rises to about 100 degrees C. at which point of time a thermostatic circuit closer 18, of any ordinary and well known construction placed in the chamber 3, closes a circuit 19, 20, from the mains 5 and 6, and thereby operates to stop the distilling and condensing of the ammonia.

This operation is effected by the following means. In the circuit 19, 20 is an electro-magnet 21, which upon the closure of said circuit attracts an armature lever 22, connected to one main by wire 23, on to a stop 24 connected by wire 25, to an electro-magnet 26, and thence by a wire 27, to the other main. The magnet 26, when energized pulls over the lever 28, of the controlling valve 12, that shuts off the flow of water from inlet 11, to the pipe 13, and the condenser coil 10, and directs the flow through a pipe 29, into water coils 30, in the distilling chamber.

The valve lever in the movement thus imparted to it tilts a pivoted circuit closer 31, and interrupts the circuit through wires 32, 33, and 34 to and through the heating coil 4. The circuit closer may be of any proper construction, but I prefer to use a glass globe with a wire 35 sealed in at the top and extending to about the level of a depression in the bottom of the same, into which another wire 36 is sealed. The globe contains an atmosphere of nitrogen and the depression a small quantity of mercury so that when the globe is in a vertical position,

the circuit between wire 35 and the mercury is completed, but when the globe is tilted the mercury runs out of the depression and breaks the circuit.

Under the conditions thus established the strong affinity of the aqueous ammonium nitrate left in the distilling chamber, for the ammonia in the refrigerating chamber, causes the latter to pass from such chamber through a pipe 37, back to the distilling chamber through a check valve 38. As there is a similar valve 8, in the pipe 7, this is the only path for the ammonia at this time. The ammonia enters the distilling chamber 3, through a device by means of which it is finely divided and delivered in a condition in which it is more readily absorbed.

As the absorption of the ammonia goes on its level in the refrigerating chamber falls, until it finally reaches a point at which a floating valve 40 encounters a lever 41, at the bottom of the tank or chamber and closes a circuit between the metal of the apparatus and a wire 42, leading to one of the mains. This completes the circuit to the other main through wire 43, including an electro-magnet 44, and draws over the armature 22, onto a stop 45, from which runs a wire 46 to wire 27, that includes an electro-magnet 26. This magnet when energized draws over the water valve lever 28, shuts off the water from the coil 30, in the distilling chamber, and directs it through the coil in the condensing chamber, and at the same time brings the circuit closer 31, to an upright position in which the circuit through the heating coil 4 is again closed.

The above description of a complete cycle of operation suffices to show that the apparatus is purely and continually automatic in its operation. In practice it has been found very economical and highly effective.

What I claim as my invention is—

1. In a refrigerating apparatus of the kind described, the combination of a distilling, a condensing and a refrigerating chamber, and a contracted orifice between the condensing and the refrigerating chambers, by which the refrigerant is liquefied and brought to a lower temperature by its passage through the same.

2. In a refrigerating apparatus of the kind described, the combination of a distilling, a condensing and a refrigerating chamber, and a passage from the condenser to the refrigerating chamber having small orifices through which the refrigerant passes gradually in fine streams.

3. In a refrigerating apparatus of the kind described, the combination of means for distilling a refrigerating composition, a condenser for liquefying the same, a refrigerating chamber and a tube connecting it with the condenser provided with one or

more orifices of very small diameter, whereby the refrigerant is delivered to the refrigerating chambers gradually and in very fine streams.

- 5 4. In a refrigerating apparatus of the kind described, the combination with the condenser and the refrigerating chamber, of a connection between them designed and adapted to secure the Joule-Thompson effect 10 in the passage of the refrigerant from one to the other.

5. In a refrigerating apparatus of the kind described, the combination with the condenser and the refrigerating chamber of a pipe leading from one to the other provided at its end in the refrigerating chamber with a disk with radial passages of small diameter extending from the bore of the pipe. 15

In testimony whereof I hereunto affix my 20 signature.

FREDERICK G. KEYES.
